UNITED STATES PATENT OFFICE.

HYMAN E. GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,728.

Specification of Letters Patent.

Patented July 21, 1908.

Application filed June 13, 1907. Serial No. 378,678.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

When a calculating machine is used in the making of bills and statements by large commercial houses such for instance as gas companies, it often happens that printed or other predetermined forms are used in which there are two or more relatively narrow columns of figures placed so close together that the total 15 of the items in a column is greater than the space allotted for the largest possible item.

To give a concrete case, suppose that it is desired to record upon a single sheet of paper, data, let each column represent whatever it 20 may, of three different classes in three different columns called "A", "B", "C", placed close together as follows:

	A	B	C
25	9174329814794242196		
	8438742946949337482		
	4926514421848147351		
	8596742754476294734		
	8429762728964982421		
30	9413520942836314936		
	4294652826428728751		
		54362977	

When now either of the two right hand columns is added as for instance "B" the total contains eight figures or one figure more than the number of figures (seven) in the column "B" so that the ten millions figure "5" would occupy a place at the left of column "B" or under the right hand or units of column "A". Similarly adding column "C" would produce a sum whose left hand figure would occupy a place under the right hand or units line of column "B". If the columns 45 of figures shown were extended vertically by the addition of more data the sums would soon run into two, three or more additional figures which would occupy places in the next column or column to the left. If such a machine as is shown in my U. S. Patent 741,961, issued October 20, 1903 or my U. S. Patent 782,554, issued February 14, 1905 or a combination of them is used with a plurality of totalizers one for each column "A", "B" and 55 "C" it is necessary to provide each totalizer

with enough recording wheels to take care of the possible total of each such main column *i. e.* with as many wheels as there are likely to be numerals in said total. In other words the totalizer for column "B" which contains only seven figures must have eight wheels to take care of the total shown in the example and a ninth wheel if the total may possibly run into the hundred millions place but each such additional wheel over seven in the totalizer "B" would necessitate a separation of columns "A" and "B" by the width of such wheel or the width of one numeral with the result that the columns A and B could not be printed close together upon the record sheet 70 of the machine as shown in the example.

The object of this invention is to solve this problem or to provide a mechanism by means of which the total of a column of a given number of figures may be accumulated within the lateral width of said column, though the total contains a greater number of figures than the number of figures crosswise in said column to be added.

The invention consists in the use of an ordinary totalizer provided with as many figure wheels as there are figures crosswise of the particular column which is to be accumulated or recorded and a supplemental counting mechanism so connected to the last or left hand figure wheel of the totalizer that any excess of figures in the total of the column is accumulated upon the supplemental counting mechanism located at some convenient point within the regular width of the regular totalizer, usually above it. In other words it consists in a "two story" totalizer but the second story for taking care of the surplus figures in the sum of the column of figures may be at any convenient point with reference to the regular wheels of the totalizer so long as the width of such regular totalizer is not increased.

Referring to the drawings Figure 1 is a front view of a calculating machine such as is fully illustrated in my two prior patents above described having the device of this invention applied thereto. The same may be sufficiently described in view of said prior patents by saying that the calculating mechanism is attached to an ordinary typewriter which in the present instance is a Remington machine. As typewriters of the Remington kind are well known in the art detailed description of the printing parts is unnecessary.

In using the machine the operator manipulates the keys 10 of the typewriter to print the figures of columns "A" "B" "C", etc. Said keys operate the stationary differential, 5 or setting mechanism 11 which accumulates the result of the calculation in the totalizers of which there are three shown viz. 12, 13 and 14, one for each of the main columns of figures A, B and C respectively illustrated in 10 the above example. If more principal columns of figures like A B and C are to be worked upon by the machine additional totalizers would be added, as set forth in the above patents. The mechanism of this invention is for clearness shown as applied to 15 the totalizer 13 whose details are illustrated in Figs. 2 and 3 but in practice totalizer 14 would be like 13 except in width so as to take care of the total of column "C" as heretofore 20 described.

Fig. 2 is a vertical sectional detail view of the totalizer 13 looking at it from the side of the machine as viewed in Fig. 1 and in the direction of the arrow 2 of Fig. 3.

25 Fig. 3 is a front view of the totalizer 13 with the cover removed. The lower half of this totalizer 13, illustrated in Figs. 2 and 3, is exactly like that of Figs. 40 to 46 inclusive of my above patent 741,961. It consists of side 30 walls 20 mounted by means of lugs 21 so as to slide laterally with the motion of the typewriter carriage. The receiving wheels 22 are loosely mounted upon the shaft 23 which is fixed in the side walls 20. Said receiving 35 wheels are free to rotate upon said shaft but are prevented from moving laterally thereon and are placed equidistant from each other, their distance apart being equal to one step of the typewriter carriage. The receiving 40 wheels are so placed that they will be brought one after another into mesh with a master or setting wheel 11^a operated by and forming a part of the differential mechanism 11. The number of receiving wheels is equal to the 45 number of figure wheels of the mechanism which, for the reasons heretofore pointed out, must not be more than the number of figures crosswise of column "B" and also determines the value of the highest number which 50 can be shown upon the totalizer "B" without the use of the invention of this application. The wheels 22 mesh with gear wheels 25 one being secured to each figure wheel 26 for rotating the latter. These figure wheels carry 55 on their periphery a series of numerals or digits for registering the total in the manner common in calculating machines. Each wheel 22 meshes with a wheel 28 upon a shaft 29. Adjacent to each wheel 28 is a 60 carrying pinion 30 mounted upon rocker arms 31 fully shown and described in Figs. 43 to 46 of the above patent 741,961.

65 Referring now to the particular totalizer 13 illustrated in Figs. 2 and 3 it is seen that there are seven figure wheels 26 and seven

figures therefore is the limit of the possible record of this machine without the addition of this invention unless the totalizer be made wider and additional figure wheels added which as heretofore described would necessarily increase the width between the columns A and B on the record paper illustrated above, which is undesirable. I therefore make the side walls 20 of totalizer 13 higher than those of totalizers 12 and 14 and in the 70 extended part mount a gear wheel 34 meshing with the adding wheel 28 of the left hand figure wheel 26 so that any surplus figures of total of column "B" greater than the seven figures, the capacity of the main or lower 75 totalizer, are carried by said wheel 34 to other gears 35 and 36 also journaled in the upper part of the totalizer. This last mentioned gear 36 meshes with a pinion 37 fast on a shaft 38. This shaft 38 is free to rotate 80 in the side walls 20. All of said gears 34, 35, 36 and 37 are at the left side of the totalizer. Rigidly mounted at the right hand end of this shaft 38 is a pinion 39 similar in construction and similarly placed to pinion 37. 85 This pinion 39 is in mesh with a receiving gear 50 loosely mounted on shaft 51 and in mesh with a carrying gear 52. Thus the carrying wheel 52 has a motion equal to that of figure wheel 26, the two being geared together by the intermediate gears 22, 28, 34, 35, 36, 37, shaft 38, and wheels 38, 50 and 52, the wheels 37 and 39 both being pinned to shaft 38. To the left of receiving gear 50 are other similar receiving gears 90 loosely mounted on the same shaft. To the left of carrying gear 52 are other carrying gears similarly constructed and similarly mounted each one carrying a gear for each receiving gear. For each receiving gear 54, 95 55 and 56 etc. there is mounted loosely upon shaft 38 figure wheel 40, 41, 42, 43, 44 in mesh therewith but there is none for the receiving gear 50 at the extreme right of the totalizer. The carrying wheels upon shaft 100 53 are geared together by means of carrying pinions 48 so that the tens of the total are carried from one to the other in a manner absolutely similar to the action of the carrying pinions 30 below.

105 The result of this construction is an adding mechanism for accumulating respectively the eighth, ninth, tenth, eleventh numerals to the left of seven figures which may occur in the total column "B" when additional data is 110 added to that shown in the example and the sum ascertained. To summarize; the result of this construction is that when this device is applied to a column of figures like the column B in the above example the main or 115 lower totalizer accumulates upon the wheels 26 the total of all figures in column "B" so long as that total does not exceed seven figures and any sum which is in excess of seven figures is taken care of and accumu- 120 125 130

lated in the upper portion of the device by the wheels 40 to 44 and all the operator has to do to get the total of the entire column is to first read the figures upon the wheels 44-40 and then place at the right of them the numerals of the wheels 26. For instance if the total of column B was 7,254,403,977 the figures 7, 25 would appear upon the wheels 41, 40, 39 respectively and be visible at 60 while the figures 4,403,977 would appear on the wheels 26 and be visible at slot 61, and the operator would get the total by combining the two partial totals in the manner described.

15 It will be seen that my totalizer is not a mere counter operable from the units end only but is an actual totalizer operable directly in more than one of its ordinal places. The upper or supplementary portion of the 20 totalizer is a mere counting mechanism being directly operated only from its right hand or units end, which operation is effected through the agency of the lower portion of the totalizer and not directly by the differential mechanism.

While I have illustrated a counting mechanism similar in construction to the totalizer shown in my previous patents that is not necessary, and any counting mechanism for 30 instance one similar in construction to any of the well known counting mechanisms say the Veeder, could have been used. It is necessary and sufficient that the figures of the total in the eighth, ninth, etc. place be 35 shown in the counting mechanism.

While in the drawings I have illustrated a totalizer 13 with side walls 20 it is not necessary that said totalizer should have independent side walls. Its shafts could be continued through the other totalizers adjacent to it namely 12 and 14 by building a special totalizer to embrace all three totalizers; 12, 13 and 14 in one mechanism. Under these circumstances the space occupied by walls 40 20 of totalizer 13 could be eliminated and the columns A, B and C could be then absolutely abutted against each other as shown in the illustration on page 1 of the specification.

50 What I claim as new and desire to secure by Letters Patent, is:

1. In combination, a laterally stationary master means, a plurality of laterally movable totalizers immediately adjacent to each 55 other and operable by said master means in more than one of their ordinal places, one of said totalizers being capable of exhibiting a total containing a greater number of digits than there are ordinal places in which said 60 totalizer is operable by said master means.

2. In combination, a group of totalizers and master means, one movable relatively to the other, the totalizers being located immediately, adjacent to each other and being 65 operated by the master means in more than

one of their ordinal places, one of said totalizers being capable of exhibiting a total containing a greater number of digits than there are ordinal places in which said totalizer is operable by said master means.

70

3. A totalizer having a plurality of groups of figure wheels each group mounted upon an independent axis and the figure wheels of the principal group being located side by side upon their axis, and the principal group being adapted to be operated in each of its ordinal places, said totalizer being adapted to exhibit a total containing a greater number of digits than there are figure wheels in said principal group.

75

4. In a calculating machine, a totalizer operable directly in more than one ordinal place and having its figure wheels side by side but arranged in two series which are not side by side to thereby reduce the total 85 width necessary to exhibit the highest number within the capacity of the totalizer.

80

5. A totalizer operable directly in more than one ordinal place and having a set of figure wheels arranged in a series side by side 90 for exhibiting a number, and other figure wheels located elsewhere in the totalizer for exhibiting those digits whose ordinal value is higher than the figure wheel of highest ordinal value in the aforesaid series of figure 95 wheels.

90

6. A calculating machine having a stationary master means and a totalizer adapted to travel past and to a point completely beyond said master means, said totalizer having 100 figure wheels and having receiving wheels, adapted to be operated by said master means, said figure wheels being greater in number than the receiving wheels, whereby a number may be exhibited in which there are more 105 figures than there are receiving wheels.

100

7. In a recording calculating machine, accumulating means comprising a totalizer and a counting mechanism adapted to supplement said totalizer, said totalizer and 110 counting mechanism each embodying figure wheels, the axes of the figure wheels of the counting mechanism being parallel to the axes of the figure wheels of the totalizer, and said counting mechanism being located laterally within the field of operation of said totalizer.

115

8. In a recording calculating machine, a plurality of totalizers for different columns of figures to be recorded in close proximity to 120 each other, each totalizer having figure wheels approximately equal to the width of the type figures and each totalizer being approximately of the width of the column it is to record, and counting mechanism located 125 within the width of the totalizer to the right for supplementing it.

120

9. In a calculating machine, stationary differential mechanism and a traveling totalizer, said totalizer including regular and sup- 130

125

plementary figure wheels, the regular figure wheels only being adapted to be operated by the differential mechanism and the supplementary figure wheels being adapted to exhibit the figures of the total of higher ordinal value than can be exhibited in the regular figure wheels.

10. A recording calculating machine having stationary differential mechanism and a plurality of totalizers traveling relatively thereto, said totalizers being directly operable in a definite number of their ordinal

places, and said totalizers being located close together and one of said totalizers being arranged to show a total greater than the number of the ordinal places in which it is directly operable by the differential mechanism. 15

In witness whereof, I have hereunto subscribed my name in the presence of two witnesses.

HYMAN E. GOLDBERG.
